"Photos of Packers deemed Prior Art by Applicant, Worldwide Oilfield Machine, Inc.", Mar. 9, 2018, 10 pages.

Primary Examiner — Sheryl Lane*Assistant Examiner* — Ieisha N Price(74) *Attorney, Agent, or Firm* — Kenneth L. Nash; Thomas D. Nash(57) **CLAIM**

The ornamental design for a ram packer, as shown and described.

DESCRIPTION

FIG. 1 is a perspective view of a ram packer.

FIG. 2 is an environmental perspective view thereof.

FIG. 3 is a top plan view thereof.

FIG. 4 is a bottom plan view thereof.

FIG. 5 is a front elevational view thereof.

FIG. 6 is a rear elevational view thereof; and,

FIG. 7 is a side elevational view thereof with the opposite side being a mirror image thereof.

The broken lines in the drawings illustrate portions of the ram packer and form no part of the claimed design.
